TRIMMING MACHINE

Lewis J. Bazzoni, Swampscott, Mass., assignor to
 United Shoe Machinery Corporation, Paterson,
 N. J., a corporation of New Jersey

Application June 14, 1933, Serial No. 675,795

27 Claims. (Cl. 12—42)

This invention relates to machines for trimming flexible material and is illustrated as embodied in a machine particularly suitable for skiving a margin of a cover which projects beyond an edge of a heel to which the cover has been applied.

In order to perform this and other skiving operations, there is provided, in accordance with one feature of the invention, an anvil for supporting the margin of a piece of flexible material, a rotary rasp and means for causing the rasp to skive the margin by a series of stock-removing operations which progress toward the edge of the margin. In the illustrated construction the rasp has pointed teeth arranged in a helix about its periphery so as to feed the material as well as to skive the margin thereof.

In order to facilitate the feeding of the material, and in accordance with another feature of the invention, the anvil is rotatably mounted. In the illustrated construction the anvil has the general form of a cylinder with its axis substantially at right angles to that of the rotary abrading rasp and substantially in tangential relation with respect to the rasp so as to form with the periphery of the rasp a V-shaped opening into which the margin to be skived is fed.

In skiving the cover margin which projects above the attaching face of the heel, it is customary to start the skiving cut about one-eighth of an inch from the rim of the attaching face of the heel to which the cover has been applied, whereas in skiving the margin which projects beyond the breast of the heel, it is customary to start the skiving cut substantially at the breast edge of the heel. To this end, in accordance with another feature of the invention, the gage which engages the covered face of the heel may be adjustably moved by a treadle toward and away from the axis of rotation of the anvil in order to position the edge of the heel at varying distances from the V-shaped opening.

These and other features of the invention, including certain details of construction and combinations of parts, will be described as embodied in an illustrated machine and pointed out in the appended claims.

In the drawings,

Fig. 1 shows a front elevational view of the illustrated machine;

Fig. 2 is an end elevational view of the machine;

Fig. 3 is a plan view of the machine;

Fig. 4 is a sectional view of the machine taken along the line IV—IV of Fig. 3;

Fig. 5 is a detail view showing a heel positioned by the gages of the machine while the margin of the cover which projects beyond the breast of the heel is supported by an anvil and is being skived by the rotary rasp of the machine;

Fig. 6 is a view corresponding to Fig. 5 showing the machine in the operation of skiving the margin of the cover projecting beyond the attaching face of the heel;

Fig. 7 is an enlarged view of a portion of the rotary rasp; and

Fig. 8 is a perspective view of a heel, the projecting margins of the cover of which have been skived in the illustrated machine.

The illustrated machine may be advantageously used to skive the projecting margins 20 and 22 (Figs. 6 and 5, respectively) of a cover 24 applied to the rear and side faces of a heel 26 preparatory to cementing the margins 20 and 22 to the attaching face 28 and to the breast 20 face 30 of the heel, respectively.

The illustrated machine is provided with a rotatable anvil 32 for supporting one of the heel cover margins 20, 22, a rasp or tool 34 rotatable in a plane disposed at substantially right angles 25 to the plane of rotation of the anvil 32 and constructed and arranged to skive or to bevel the margins 20, 22 of the cover supported by the anvil 32 by a series of cuts (Fig. 8), each of which progresses toward the edge of the margin 30 being operated upon, and a pair of rotatably mounted gages 36, 38 constructed and arranged to engage the covered and the uncovered faces respectively of the heel for guiding the same and one of the projecting margins of the cover 35 relatively to the rasp 34.

The rotary rasp 34 is secured by screws 40 (Fig. 5) to a flange portion 42 (Fig. 3) of a shaft 44 which is supported for rotation in a bearing housing 46 mounted upon the main frame. A 40 pulley 48 (Fig. 3) is keyed to the opposite end of the shaft 44, the pulley being driven by a belt 50 which receives its power from a pulley 52 of an electric motor 54. The lower half of the rasp 34 is positioned within a guard 56, the 45 outer side of which is removable for the purpose of changing the rasp.

The anvil 32 which is illustrated as formed integral with the gage 38, and may be referred to as a drum, is secured to an upright shaft 58 50 (Figs. 5 and 6) which is rotatably mounted in a U-shaped arm 60 having hub portions 62 (Fig. 3) which are mounted upon a pin 64 carried by a bifurcated bracket 66. A driving pulley 68 (Fig. 1) is keyed to the lower end of the shaft 58. The 55

U-shaped arm 60 and the bifurcated bracket 66 are normally locked together by a pair of screws 67 which are arranged transverse to the axis of rotation of the shaft 44 and which are in threaded relation with the U-shaped arm 60 and have their end faces in engagement with the bifurcated bracket 66.

The lower portion 76 (Figs. 5 and 6) of the side surface of the drum is inclined toward the axis 10 of rotation of the anvil 32 from the point 72 of substantial contact of the rasp 34 and the anvil 32 which may be said to have a cylindrical surface arranged in substantially tangential relation with respect to the rasp. The upper corner 15 of the anvil 32 is beveled to facilitate the bending of the margin of the cover of the heel guided by the gages 36, 38 into a V-shaped opening 74 (Fig. 2) formed between the anvil 32 and the rasp 34. The opening through which the cover is fed during 20 the skiving operation may be said to be V-shaped in two directions disposed at substantially right angles to each other.

In order initially to adjust the anvil 32 toward and away from the rasp or scraping tool 34, 25 the bifurcated bracket 66 to which the U-shaped arm 60 is clamped by screws 67, is mounted for pivotal adjustment upon upper and lower flat surfaces (Fig. 4) of the bearing housing 46 about a bolt 78 carried by the bearing. Such adjustment 30 is effected by turning screws 76 which are spaced in the general direction of the axis of the shaft 44 and are in threaded relation with the bifurcated bracket 66 and have their ends in engagement with the bearing housing 46. To assist 35 the operator in making this adjustment, the bifurcated bracket 66 is provided with an arcuate slot 80 (Fig. 3) through which passes a screw 82 which is in threaded relation with the bearing housing 46. When it is desired to adjust the anvil 32 toward or away from the rasp 34 the screws 76 are loosened and the bifurcated arm 66, after being turned to its proper angular position about the bolt 78 is held in place by the screw 82, after which the screws 76 are set up against the bearing housing 46. Lubricant may be supplied 40 to a bearing 84 of the shaft 44 through a wick 88 the lower end of which is inserted in an oil chamber 86 of the housing 46.

The rotatable gage 36 which has a general shape 50 of a bowl encloses the upper part of the rasp 34 and serves as a guard. Secured to the gage 36 is a shaft 90 which is rotatably mounted in a bearing 92 provided with a sleeve portion 94 journaled upon a pin 96 supported by a bearing portion 98 of the main frame. A gage driving pulley 100 is keyed to the upper end of the shaft 90.

The pulley 68 which rotates the combined anvil 32 and gage 36 is driven through a belt 102 (Fig. 1) by a pulley 104 secured to the lower end 60 of a countershaft 106. The countershaft 106 is journaled in bearing housings 108 supported by a standard 110 of the main frame. The pulley 100 through which the gage 36 receives its power is driven by a belt 112 which is in driving relation 65 with a pulley 114 secured to the upper end of the countershaft 106.

The countershaft 106 is provided with a gear 116 (Fig. 3) which meshes with a worm 118 of a shaft 120 mounted in bearing housings 122 and 70 124 (Fig. 1). Mounted upon the shaft 120 is a driven clutch member 126 which carries a pin 128 arranged to pass through an elongated slot 130 formed in the shaft 120. With such an arrangement, it will be noted that the driven member

126 is rotatable with the shaft 120 but is movable lengthwise of the shaft. A pulley 132 which is formed integral with a driving clutch member 134 is mounted for rotation upon the shaft 120 and is normally in driving relation with the driven member 126 which is urged against the driving member 134 by a spring 136. The machine is provided with a treadle operated cam 138 having a cam surface 140 which is arranged to engage one end of a rod 142 mounted for reciprocation in an axially extending recess of the shaft 120 and the other end of which engages the pin 128 carried by the driven member 126. Movement of the cam 138 causes the rod 142 to force the driven member 126 to the right against the pressure of the spring 136 thereby to throw the member 126 out of driving engagement with the driving member 134. The pulley 132 is rotated by a belt 146 (Fig. 3) which is driven by a pulley 148 of the electric motor 54.

As above stated, in skiving the margin 20 (Fig. 6) which projects beyond the attaching face 28 of the heel, it is desirable that the skiving cut shall start about one-eighth of an inch from the rim of an attaching face, whereas the skive formed 25 on the margin 22 (Fig. 5) which projects beyond the breast of the heel shall start substantially at the breast edge of the heel. Accordingly, the gage 36 is mounted for swinging adjustment about the pin 96 in order to adjust such gage toward 30 and away from the axis of rotation of the anvil 32. The gage 36 may be readily swung by the operator alternatively to the positions shown in Figs. 5 and 6, with respect to the anvil 32 by lowering and raising a treadle-operated rod 150 35 (Fig. 2) which is connected to an extension 152 of the sleeve 92.

Upward movement of the rod 150 causes a lug 154 of the extension 94 to engage a screw 156 which is adjustably mounted in the main frame 40 and downward movement of the rod 150 moves another lug 158 into engagement with a screw 160 which is also adjustably mounted in the machine frame. The screws 156, 160 may be initially adjusted to control the swinging movement 45 of the gage 36 in accordance with the position at which it is desired to form the bevel on the projecting margin of the cover to be skived.

In skiving margins of flexible material, it is sometimes desirable to vary the angle of the skive 50 and accordingly the anvil 32 may be angularly adjusted about the axis of the pin 64 (Fig. 4) which axis, as already stated, is disposed in parallel relation with respect to the axis of rotation of the rasp 34 and passes through the bottom of 55 the V-shaped opening 74. Such adjustment may be readily effected by turning screws 67, which are carried by the U-shaped arm 60 and the ends of which engage the bifurcated bracket 66, in opposite directions until the desired adjustment 60 has been made.

In order to expedite the feeding of the margin through the V-shaped opening 74 the rasp 34 comprises a plurality of pyramidal teeth 162 (Fig. 7) arranged in the form of a helix. To assist in 65 feeding the margin into the V-shaped opening 74, the end of the rasp 34 to which the work is first presented is provided with a conical surface 164.

In order to perform the skiving operation the 70 operator, after making the necessary adjustments, engages a covered face of the heel with the gage 36 and rests the face beyond which the cover projects against the gage 36. As the heel is guided past the cutter from left to right (Fig. 1) 75

5 by the gages the projecting margin which passes through the space formed between the gages 36, 38 and through the V-shaped opening 74, is forced by the rasp 34 against the cylindrical face of the anvil 32 and is skived by a scraping cut which progresses toward the edge of the margin. The rasp 34, thus, not only straightens out the margin as it forces the same against the anvil 32 but also, due to the spiral arrangement of the teeth, assists 10 in feeding the margin past the anvil thereby to insure that there is no wrinkling of the flap during the skiving operation.

15 The machine of the present application is similar in many respects to the machine of application Serial No. 675,794, filed June 14, 1933, in my name, and all subject-matter common to the two applications is claimed in said above-identified application.

20 Having thus described my invention, what I claim as new and desire to secure by Letters Patent of the United States is:

25 1. A trimming machine having, in combination, a rotary anvil for supporting the margin of a piece of flexible sheet material fed over it, a cooperating stock-removing tool, and means for rotating said tool in a plane disposed at an angle to the plane of rotation of the anvil and in a direction to skive the margin by a series of operations which progress toward the edge of the 30 margin.

35 2. In a trimming machine, a rasp mounted for rotation about an axis, an anvil having a work-engaging face constructed and arranged to be engaged progressively by an elongated projecting margin of a piece of flexible material secured to a block, and means constructed and arranged to be engaged by the block for guiding said projecting margin generally lengthwise of the axis of rotation of said rasp to skive the margin by a series of cuts which progress toward the edge of 40 said margin.

45 3. In a trimming machine, a rasp mounted for rotation about an axis, and an anvil having a work-engaging face curved about an axis disposed at a substantial angle to the axis of rotation of the rasp, said rasp being constructed and arranged to skive to a feather edge a projecting margin of a cover, which is attached to a heel and is supported by the anvil, by a series of cuts 50 which progress toward the edge of the margin.

55 4. In a trimming machine, a rasp rotatable about an axis, and an anvil rotatable about an axis disposed at substantially a right angle to the axis of rotation of the rasp, said anvil being provided with a work-engaging face constructed and arranged to be progressively engaged by an elongated margin of a piece of flexible material which forms the cover of a heel to brace the same against the action of the rasp thereby to 60 skive the margin to a feather edge by a series of cuts each of which progresses toward the margin of the cover.

65 5. A trimming machine having, in combination, a rotary anvil shaped and arranged to support a cover margin projecting beyond an edge of a heel to which the cover has been applied, a rotary rasp arranged almost to engage the anvil, and gages for positioning the heel and its projecting margin relatively to the anvil, opposed portions of the anvil and the rasp being mounted for movement in planes disposed substantially at right angles to each other.

70 6. A trimming machine having, in combination, a rotary anvil for supporting a margin of a cover projecting beyond an edge of a heel to

which the cover has been applied, a rotary rasp arranged almost to engage the anvil, and gages for positioning the heel and the projecting margin of said cover relatively to the anvil, opposing portions of the anvil and the rasp being mounted 5 for movement in planes disposed at substantially right angles to each other, said rasp being constructed and arranged to feed said margin past the anvil as it skives the cover margin supported by said anvil.

10 7. A trimming machine having, in combination, a scraping tool, and a rotary anvil provided with a face constructed and arranged to form with the scraping tool, an opening which is V-shaped in two directions disposed at substantial 15 angles to each other.

15 8. A trimming machine having, in combination, an anvil provided with a cylindrical surface for supporting a margin of flexible material, and a rotary rasp arranged substantially in engagement with said surface to provide a V-shaped opening into which said margin may be fed, said anvil being rotatable about an axis which lies substantially in the plane of rotation 20 of the rasp.

25 9. A trimming machine having, in combination, a rotary scraping tool, and a rotary anvil constructed and arranged to form with the tool an opening which is V-shaped in two directions disposed at substantial angles to each other, said 30 tool comprising a plurality of teeth arranged in a helical series.

35 10. A trimming machine having, in combination, an anvil for supporting a flexible heel cover margin which projects beyond one of the edges 35 of a face of a heel to which the cover has been applied, a rotary rasp comprising a plurality of teeth arranged in a helical series and constructed and arranged for cooperation with the anvil to skive said margin by a plurality of cuts each of 40 which progresses toward the edge of said margin, and means for guiding the heel relatively to the rasp to determine the location of the trimming cuts.

45 11. In a trimming machine, a rasp mounted 45 for rotation about an axis and provided with teeth arranged in a helical series, an anvil mounted for rotation about an axis disposed at a substantial angle to the axis of rotation of the rasp, said anvil being constructed and arranged 50 to present the margin of a flexible piece of covering material secured to a heel progressively to the rasp, and means for operating the rasp to cause the margin supported by the anvil to be skived by a series of cuts each of which progresses 55 toward the edge of the margin.

60 12. In a trimming machine, a rasp movable in a predetermined path, an anvil for supporting the projecting margin of a cover secured to a heel against the rasp, and a member constructed 60 and arranged to be progressively engaged by the heel and to guide said margin in a path disposed at a substantial angle to the path of movement of the rasp thereby to skive the margin by a series of cuts each of which progresses toward 65 the edge of the margin of the cover.

70 13. A trimming machine having, in combination, a rotatable anvil for supporting a margin of a flexible cover which projects beyond one of the edges of a face of a heel to which the cover 70 has been applied, a scraping tool rotatable in a plane disposed at substantial right angles to the plane of rotation of the anvil and constructed and arranged to skive the margin of the cover supported by said anvil by a series 75

- of scraping cuts which progress toward the edge of said margin, and means constructed and arranged to engage simultaneously both the covered face and another face of the heel for positioning the heel relatively to the cutter thereby to determine the location of the trimming cut.
14. A trimming machine having, in combination, a rotary drum for supporting a margin of a flexible cover which projects beyond one of the edges of a heel to which the cover has been applied, a gage to engage a covered face of the heel, said drum having a surface arranged to engage another face of the heel, and a rotary tool constructed and arranged to force the margin of the cover against the drum to skive the projecting margin fed past the drum to a predetermined width.
15. A trimming machine having, in combination, a rotary tool provided with a face having stock removing projections thereon, and a drum rotatable about an axis which lies substantially in the plane of rotation of the tool, said drum being arranged adjacent to the face of the tool to form a V-shaped opening through which a projecting margin of a cover attached to a heel may be moved thereby to skive said margin to a feather edge.
16. A trimming machine having, in combination, a rotatable drum provided with a surface for supporting the projecting margin of a cover secured to a face of a heel, a gage for engaging the covered face of the heel, said drum comprising a surface arranged to engage the face of the heel beyond which said cover margin projects, and a rotary tool arranged adjacent to said margin supporting surface and constructed to skive the margin of the cover by a series of scraping cuts each of which progresses toward the edge of the margin.
17. A trimming machine having, in combination, a pair of rotatable gages spaced from each other and constructed and arranged to engage angularly disposed faces of a heel beyond one of the edges of which projects a margin of a cover which has been applied to the heel, an anvil to support the projecting margin of the cover, and a rotary tool having a plurality of circumferentially spaced teeth movable in a path which is disposed substantially in tangential relation with respect to said anvil thereby to skive the margin supported by the anvil.
18. A trimming machine having, in combination, a rotary tool provided with a roughened face, a drum rotatable about an axis which lies substantially in the plane of rotation of the tool, said drum being arranged adjacent to the roughened face of the tool to form a wedge-shaped opening through which a projecting margin of a cover attached to a heel may be moved thereby to skive said margin to a feather edge, and means for angularly adjusting said drum about an axis disposed substantially parallel to the axis of rotation of the tool and passing substantially through the bottom of the V-shaped opening.
19. A trimming machine having, in combination, a pair of rotatable gages spaced from each other and constructed and arranged to engage angularly disposed faces of a heel beyond one of the edges of which projects a margin of a cover which has been applied to the heel, an anvil to support the projecting margin of the cover, a rotatable scraping tool movable in a path which is disposed in substantially tangential relation with respect to the anvil thereby to skive the margin supported by the anvil and fed past the same, and means for positively rotating the gages and the anvil to facilitate the feeding of the cover past the tool.
20. A trimming machine having, in combination, a rotary anvil for supporting a margin of a cover projecting beyond an edge of a heel to which the cover has been applied, a rotary rasp arranged in tangential relation with respect to the anvil for skiving the margin to a feather edge, gages spaced from each other and constructed and arranged for engagement with the covered face of the heel and the face of the heel beyond which the cover margin projects respectively, said rasp comprising a series of teeth arranged in the form of a helix for feeding said margin past the anvil, and means for moving the gages to feed the heel past the anvil.
21. A trimming machine having, in combination, a rotary drum for supporting a margin of a cover which projects beyond an edge of a heel to which the cover has been applied, a gage to engage a covered face of the heel, said drum having a surface arranged to engage another face of the heel, a rotary tool constructed and arranged to force the margin of the cover against the drum thereby to skive the projecting margin of the cover to a predetermined width, and means for adjusting the gage relatively to the drum to vary the position of the skive with relation to said edge of the heel.
22. A trimming machine having, in combination, a rotary tool provided with a roughened face, and a drum rotatable about an axis which lies substantially in the plane of rotation of the tool, said drum being arranged in substantially tangential relation with respect to the face of the tool to form a V-shaped opening through which a projecting margin of a cover attached to a heel may be fed thereby to cause the tool to skive said margin, the drum being adjustable about an axis which extends substantially lengthwise of the axis of rotation of the tool and passes substantially through the bottom of the V-shaped opening thereby to vary the shape of the opening.
23. A trimming machine having, in combination, a rotary rasp and a rotatable anvil constructed and arranged to form an opening which tapers in two directions disposed substantially at right angles to each other and is shaped to receive a margin of a piece of flexible material, and means for rotating the rasp to cause the margin fed through the opening to be forced against the anvil and thereby to be beveled by a series of scraping cuts.
24. A trimming machine having, in combination, a rotary rasp and an anvil arranged to form a V-shaped opening for receiving a margin of a cover which projects beyond one of the edges of a face of a heel to which the cover has been applied, said rasp comprising a plurality of teeth arranged in the form of a helix, means for rotating the rasp to cause the margin fed through the V-shaped opening to be forced against the anvil and thus to be skived to a feather edge by scraping cuts which progress toward the bottom of the opening, and gages constructed and arranged to engage angularly disposed surfaces of the heel for guiding the same and the projecting margin of its cover relatively to the rasp.
25. A trimming machine having, in combination, an anvil for supporting a flexible margin of a cover which projects beyond an edge of a

heel face to which a cover has been applied, a rasp mounted for movement in a predetermined path, means for guiding the heel past the rasp, and means for moving the rasp along said path to cause the same to skive the margin supported by the anvil and guided by said gages.

26. A trimming machine having, in combination, an anvil provided with a cylindrical surface for supporting a margin of flexible material, and a rotary rasp arranged for substantial engagement with said surface and shaped to form with the anvil an opening having the general shape of a letter V and through which said margin may be fed, said anvil being rotatable about an axis 10 which lies substantially in the plane of rotation of the rasp and being adjustable about an axis 15 which is disposed substantially parallel to the

axis of rotation of the rasp and passes through the bottom of said opening.

27. In a trimming machine, a rasp rotatable about an axis, an anvil mounted for rotation about an axis disposed at a substantial angle to the axis of rotation of the rasp, said anvil being constructed and arranged to support the projecting margin of a cover secured to a heel against the rasp, and a member constructed and arranged to be progressively engaged by the heel to guide the margin in a path disposed generally lengthwise of the axis of rotation of the rasp and past the rasp to skive the margin of the cover by a series of cuts each of which progresses toward an adjacent edge of the margin of the cover. 5 10 15

LEWIS J. BAZZONI.
